UNITED STATES PATENT OFFICE.

KARL J. MOSEBACH, OF PITTSBURGH, PENNSYLVANIA.

TERMINAL STRUCTURE FOR RAIL BONDS.

Application filed June 23, 1925. Serial No. 39,016.

My invention relates to electrical terminal structures for railway bonds and to the manner in which said structures are applied to the rails.

5 One object of my invention is to provide a terminal of such form that it may be more easily secured to a track rail than those heretofore constructed.

10 Another object of my invention is to provide a terminal arrangement of such form that a better electrical contact between the conductor or cable portion of the bond and rail is secured.

15 Still another object of my invention is to simplify and improve generally the structure of electrical terminals.

20 One form which my invention may take is shown in the accompanying drawing, wherein Fig. 1 is a perspective view of a portion of a railway track to which my invention is applied; Fig. 2 is a plan view of a portion of the structure of Fig. 1, on an enlarged scale; Fig. 3 is a cross sectional view of the structure of Fig. 1, and Fig. 4 is a perspective view of the terminal which is shown more clearly in Fig. 2.

25 For purposes of illustration I have shown two railroad rails 5 and 6 that may be connected by a splice bar 7 in the usual manner. The splice bar 7 is held in place by the ordinary bolts 7^a.

30 The electrical bond connecting these rails consists of a cable 8, preferably of copper, to whose ends are secured terminal members 9 preferably stamped from sheet metal. My invention resides primarily in the form of the terminals 9 and the manner in which they are mechanically and electrically connected to the rail sections and to the cable 8.

35 As shown more clearly in Fig. 4, the terminals 9 are each provided with the flat body portion 10 which is disposed beneath the underside of the rail as shown in Fig. 3. Extending upwardly and forwardly from the flat portion 10 is a curved portion 11 that is preferably formed by striking it up from the body portion 10 of the terminal. An opening 12 is thus provided directly above the flat portion 10 wherein steel or other metal may be deposited by arc-welding or otherwise, when the terminal is in place against the edge of the rail base, to firmly secure said terminal to the base.

40 The upper portion 11 of the terminal has a forwardly extending lug 13 that lies upon the upper face of the rail base and extends

to approximately the web of the rail. In making the blank, a projection 14 is provided similar to 13 but this projection is bent to circular form as shown in Fig. 3, to tightly grip the end of the cable 8. After the terminals 9, with the cables 8 clamped theron by the eye portions 14, are applied to the rail, a conducting metal such as copper is deposited in the pocket formed between the web of the rail and the projections 14 and 13 of the terminals, preferably by arc welding. I prefer to employ copper because of its relatively great conductivity and the fact that it will readily unite with the exposed end of the cable 8 and also fuse to the rail.

45 If desired, the metal deposited in the pocket referred to may be alone depended upon to maintain the clip in place, and the step of depositing metal in the opening 12 dispensed with.

50 By so constructing the terminals 9 that their eye portions 14 lie close to the web of the rail, the cable 8 will lie snugly against the vertical wall of the splice bar 7 and be protected somewhat by the heads of the bolts 7^a, from injury. Similarly, the terminals will lie somewhat under and be protected by the rail head.

55 From the foregoing it will be seen that I provide a structure of simple form which may be readily applied to a railroad track rail and which constitutes an effective electrical connection between the adjacent rail sections.

I claim as my invention:

1. Terminal structure comprising a cable, a clip of sheet metal having a portion adapted to engage one side of the rail base, and a portion struck up therefrom adapted to engage the other side of said rail base, an extension on said last-named portion adapted to be secured to the cable end, and another extension on the last-named portion spaced from the cable end in a direction longitudinally thereof.

2. Terminal structure comprising a cable, a clip of sheet metal having a portion adapted to engage one side of the rail base, and a portion struck up therefrom adapted to engage the other side of said rail base, an extension on said last-named portion adapted to be secured to the cable end, and another extension on the last-named portion spaced from the cable end in a direction longitudinally thereof, the said struck up portion

extending along either side of said first-named portion to form a pocket upon the adjacent side of the rail base for the reception of molten metal.

- 5 3. Terminal structure comprising a cable, a clip adapted to engage upper and lower surfaces of a rail base, a projection on said clip bent to circular form and surrounding the cable, and a second projection on the 10 clip, disposed adjacent to said first named projection and forming one wall of a pocket for the reception of molten metal, the cable end protruding from said circular portion in position to be united with said molten 15 metal.

4. Terminal structure comprising a cable, a clip adapted to engage upper and lower surfaces of a rail base, a projection on said clip bent to circular form and surrounding the cable, and a second projection on the 20 clip, disposed adjacent to said first-named projection and forming one wall of a pocket for the reception of molten metal, the cable end protruding from said circular portion in position to be united with said molten metal 25 which also fuses with the rail base.

In testimony whereof I, the said KARL J. MOSEBACH, have hereunto set my hand.

KARL J. MOSEBACH.
